JESSE R. MOSER, OF TOLEDO, OHIO, ASSIGNOR TO THE SURFACE COMBUSTION CO., INCORPORATED, OF TOLEDO, OHIO, A CORPORATION OF NEW YORK

CONVEYING APPARATUS

Application filed March 11, 1930. Serial No. 434,991.

The invention relates to conveying apparatus, and finds particular application in conveying apparatus for furnaces, particularly carburizing furnaces. The objects in view are serviceability and durability under the necessarily rough conditions of use with the attendant circumstance of high and widely varying temperature. The invention has been developed in application to a carburizing furnace—that is to say, a furnace in which iron or steel articles are first heated from a relatively low temperature to a temperature ranging to as much as 1450°-1650° F., more or less, and then allowed to cool again, and in such application I shall show and describe it. Its wider applicability, to furnaces dealing with other particular materials for other particular ends will be understood by the engineer.

In the accompanying drawings Fig. 1 is a fragmentary view in vertical and longitudinal section, on the plane indicated by the line 1—1, Fig. 5, of a carburizing furnace in the structure of which my invention is embodied; Fig. 2 is a fragmentary view in horizontal section through the furnace, and shows in plan from above the floor of the furnace with its conveyor equipment for sustaining and carrying material which advances through the furnace; Figs. 3 and 4 are fragmentary views to larger scale and in longitudinal and transverse sections, respectively, and illustrating details of such conveyor equipment. The plane of section 35 of Fig. 4 is in Fig. 3 indicated by the broken line 4—4. Figure 5 is a fragmentary view to larger scale than Figs. 1 and 2, showing the furnace, partly in end elevation, partly in vertical and transverse section, on the plane indicated at 5—5, Fig. 1. In Fig. 5 only the upper portion of the floor appears: the supporting structure of Fig. 1 is not shown; Figs. 6, 7, and 8 are fragmentary views to larger scale, showing in plan, in vertical and transverse section, and in horizontal section, details of the conveyor equipment of the furnace floor.

Referring to Figs. 1 and 5, the furnace will be seen to be of tunnel form, adapted to allow material to advance in continuous

course, in at one end, through the tunnel, and out at the other end. The progress of material through the furnace may be understood to be from left to right, as seen in Fig. 1. The tunnel within is shown to consist of a plurality of parts, distinguished in the height of the tunnel arch, connected in continuity. Beginning at the end on the left, Fig. 1, the material enters a chamber 1 whose arched roof is relatively low; it advances thence to a chamber 2 of higher roof, and from chamber 2 to a central chamber 3 whose roof is higher still. From chamber 3 the material advances through chambers 4 and 5 to the exit. Chambers 4 and 5 correspond in length and in height of roof to chambers 2 and 1 respectively, and the chamber structures of the two ends are symmetrical one to the other, as shown in Fig. 1. Manifestly, the progress of material through the furnace might be in either direction, and may be at one time in one direction and at another time in opposite direction; but, for purposes of description, the direction is assumed to be from left to right. In the tunnel walls and floor, within the central chamber 3, burners 6 are set, and from these burners, it may be understood, flames will spring. No chimney is provided; but the flames, filling the central chamber 3, stream thence through the tunnel in both directions, and the products of combustion emerge at the two open ends. The dimensions of the tunnel and of its constituent chambers, the thickness of the walls and roof, and the particular materials employed, will be such as the engineer, proceeding with his knowledge of the art, will choose, to establish the desired temperature range and gradients. The material, entering, is enveloped in an atmosphere which is in the succeeding chambers 1, 2, and 3 of successively higher temperature, until in chamber 3 it is of maximum degree. In its further progress the material is, in chambers 4 and 5, enveloped in an atmosphere of diminishing temperature, and is correspondingly cooled.

Referring to Fig. 5, it will be seen that the particular furnace chosen for purposes

of illustration is a four-row furnace. It will be seen, further, that in this furnace the material is carried in boxes 7; and these boxes 7, it may be understood, are pushed through the furnace tunnel from end to end, suitable pushing means being provided, as the art well knows.

The furnace floor is equipped with conveyor disks 8, and the boxes are provided with guides 9, by means of which they are retained in position, mounted upon sets of aligned disks 8. Upon such conveyor structure the boxes rest and are carried, as they are pushed through the furnace. It is with the conveyor disks 8 and their mounting in the furnace floor that my invention has to do. The end in view is a structure which, under the rough and severe conditions of service and under the varying and fluctuating conditions of temperatures, shall during prolonged intervals of continuing operation afford smooth travel; shall be relatively free of accident or delay; shall require minimum interruption; and shall involve but a small cost of maintenance.

The floor structure includes a succession of transversely set piers 10. These piers are shouldered, and between successive pairs, and overlapping the shoulders, floor sections 11 are built. It will be remarked in Figs 1 and 3 that space is provided for longitudinal play of floor sections 11 relatively to piers 10, to allow for thermal expansion and contraction. Upon the floor sections 11 pillars 12 are set and these pillars 12 together with the upper ends of piers 10 constitute a succession of supporting members, spaced apart longitudinally of the tunnel, that flame may circulate through; and to the same end the piers and pillars may be provided with longitudinally extending passageways or flue spaces, as indicated at 13, Figs. 4 and 5. Certain of the burners 6 may, as shown in Fig. 1, be situated to deliver their flames to the spaces between these supports.

Lines of lintel-blocks 14 rest upon piers 10 and pillars 12 and bridge the spaces at which piers and pillars stand apart. The blocks 14 extend in continuous lines from end to end of the tunnel, as will be perceived on comparing Figs. 1 and 6. The successive blocks in line are so spaced as to allow for longitudinal expansion and contraction under varying conditions of heat, and this feature also is indicated in the drawings. The piers 10 and the pillars 12 are at their upper ends provided with re-entrant recesses, in which the ends of the lintel-blocks 14 are received, to prevent the lintel blocks from displacement and to keep them aligned. There are in the furnace of the drawings eight lines of lintel-blocks 14. This appears on comparison of Figs. 2 and 5. All 65 the structure described—piers, floor sections,

pillars, and lintel-blocks—is built of refractory and heat-insulating material: fire-brick or its equivalent.

Upon each line of lintel-blocks 14 rests a rail 15. The rail 15 is essentially U-shaped in cross-section and rests upon the lintel-blocks with its parallel webs extending vertically upward, as most clearly shown in Fig. 7. At intervals the webs of the rail are provided with opposite bearings for the trunnions 16 of disks 8. The surfaces of the opposite bearings which the trunnions of the disk engage are concave and shaped to a common spherical surface, and the trunnions are convex and of a shape generated by the rotation of a segment of a circle upon its cord, and are of such dimensions that when the disk is in position in its bearings its trunnions engage the bearings along lines which lie in a single circumference, to the end that the disks in tipping laterally shall always have such extended engagement between the trunnions and their bearings. Thus the disk resting by gravity in the bearings, may adjust itself to minor conditions of misalignment, and may under necessity move to such an oblique position as in Fig. 7 is indicated in dotted lines, and yet the strains will not be concentrated, but will be distributed throughout the extent of the arcs of bearing contact.

Each rail is made up of sections, corresponding in length to the distance between piers 10. The piers are provided each with a saddle 17 built into the masonry, as is best shown in Figs. 3 and 4, and between opposite sides of each saddle the adjacent ends of two sequent rail sections are pinned. The pin holes, at one end at least of each rail section, are elongate, to permit thermal expansion and contraction of the rail section upon its support. The webs of the rails between the successive pairs of bearings are cut away, from the upper edges downwardly, as in Fig. 3 is indicated at 18. By such excisions the tendency of the rails to bow upwardly, when heated more highly above than below, is counteracted and practically eliminated.

As appears in Fig. 5, the boxes 7 are carried, each on a pair of rails 15. Means are provided for maintaining the rails of each pair permanently in properly spaced relation one to the other. Such means are found in a succession of dumb-bell shaped blocks 19 whose opposite enlarged heads fit snugly but with freedom of play, and yet secure against separation, in opposite pairs of sockets 20, formed at intervals upon the inner faces of the two rails of each pair.

The blocks 19 are tension members, preventive of separation of the rails, and they are compression members also, in that they prevent the rails from moving one toward the other.

Further means are provided for maintaining the pairs of rails in proper spacing, pair from pair, and from the side walls of the furnace. Round-ended blocks 21, fitting at their ends in sockets 22 formed in the furnace walls 30 and in sockets 23 formed on the adjacent rails, and other round-ended blocks 24, fitting at their ends in sockets 25 formed in the rails, constitute such means. 5 The blocks 19, 21, 24, with their sockets, are arranged in aligned groups, as shown in Fig. 6, and the groups succeed one another at intervals, throughout the length of the tunnel. By virtue of the rounding of 10 the ends of the blocks and of the corresponding rounding of the bottoms of the sockets, provision is made for relative longitudinal movement of the parts, which in some degree under varying conditions of temperature is inevitable. The drawings show the 15 sockets to be provided with webs which, when the parts are in place, extend above the heads of the blocks. These webs prevent the escape of the blocks from the 20 sockets.

In making assembly the blocks 19, 21, 24 are laid in position on the refractory supports (the blocks 21 being slipped to place in the sockets 22 in the side walls), and the 25 rails are then brought to place upon the supports, with their sockets surrounding the heads of the blocks. This manner of assembling is characterized by a simplicity which manifestly is advantageous; furthermore, when a rail is to be replaced, it is lifted off and the new rail is applied, without disturbance of other parts.

I claim as my invention:

1. In conveying apparatus a pair of bearings with bearing surfaces conforming to a common spherical surface, and a trunnioned disk whose trunnions resting upon said bearings engage the bearing surfaces along lines which are arcs of a common circumference. 45

2. In conveying apparatus a pair of bearings with concave bearing surfaces conforming to a common spherical surface, and a trunnioned disk whose trunnions resting 50 upon said bearings engage the bearing surfaces along lines which are arcs of a common circumference.

3. In conveying apparatus a pair of bearings with bearing surfaces conforming 55 in cross-section to a common circumference, and a trunnioned disk whose trunnions rest upon said bearings, the bearing surfaces of said trunnions upon an axial plane conforming to a common circumference of equal 60 radius to that of said bearings.

4. Conveying apparatus including a pair of rails provided on their opposite faces with a pair of sockets and a spacer-block extending between said rails and engaged by 65 said sockets.

5. Conveying apparatus including a pair of rails provided on their opposite faces with a pair of round-bottomed, narrow-throated sockets, and a compression and tension block of dumb-bell shape extending between said rails, its heads being engaged within said sockets. 70

6. In conveying apparatus for a heating furnace the combination with the opposite walls of a furnace chamber of a rail structure arranged between the furnace walls and including a pair of rails provided on their opposite faces with a pair of sockets, a spacer-block extending between said rails and engaged by said sockets, and spacer-blocks arranged between the furnace walls and the said rail structure and aligned with the spacer-block first named. 75

7. In conveying apparatus for a heating furnace the combination with the opposite walls of a furnace chamber of a plurality of pairs of rails, the rails of each pair being provided on opposite faces with a pair of sockets, spacer-blocks extending between the rails of each pair and engaged at their ends by said sockets, spacer-blocks arranged between adjacent pairs of rails, and spacer-blocks arranged between the chamber walls and adjacent rails, the spacer-blocks of the three said categories being aligned transversely of the furnace chamber. 85 90

8. In conveying apparatus for a heating furnace a conveyor rail adapted to rest upon the furnace floor and a rail-spacing block adapted to rest upon the furnace floor, the rail being provided with a block-engaging pocket adapted in the placement of the rail upon the furnace floor to come to position in engagement with a previously placed block, the pocket being provided with a block-retaining web which in the assembly 100 extends above the block.

In testimony whereof I affix my signature.
